CHARLES E. CASGRAIN, OF CHICAGO, ILLINOIS.

ATTACHMENT FOR BUTTONHOLE MACHINES.

1,404,372.

Specification of Letters Patent. Patented Jan. 24, 1922.

Application filed September 10, 1920. Serial No. 409,361.

To all whom it may concern:

Be it known that I, CHARLES E. CASGRAIN, a citizen of the United States, and a resident of Chicago, in the county of Cook, 5 State of Illinois, have invented certain new and useful Improvements in Attachments for Buttonhole Machines, of which the following is a specification.

My invention relates to buttonhole machines and more particularly to an attachment therefor by means of which the stitching and cutting may be stopped immediately by the operator in case something goes wrong, as for example, breaking of a needle 10 or thread, shifting of the goods worked upon, or other causes. My invention is designed particularly for association with the well known type of machine known as the Reece machine. In this type of machine, 15 the stitching mechanism first operates to stitch for the buttonhole and then the cutting mechanism becomes operative to cut the hole. The operator is provided with means for stopping further stitching in case something goes wrong, but no provision is made 20 to assure prevention of the cutting operation by the knife after the stitching mechanism has been stopped and on account of this, work is frequently spoiled. The main 25 object of my invention is, therefore, to provide mechanism which can be readily attached to existing machines and which when operated will not only immediately stop the stitching mechanism but will also positively 30 block operation of the cutting mechanism. 35 With my attachment therefore the stitching may go wrong but the stitches can be readily withdrawn. But there is no chance for erroneous cutting and the work will not be 40 ruined.

On the accompanying sheets of drawings, I have shown just enough of a Reece buttonhole machine to illustrate the purpose and operation of my improved attachment. On 45 these drawings,

Fig. 1 is a side elevational view,

Fig. 2 is an enlarged sectional view substantially on plane 2—2, Fig. 1.

Fig. 3 is a sectional view on plane 3—3, 50 Fig. 2.

Fig. 4 is a sectional view similar to that of Fig. 3, showing different relative positioning of operative parts,

Fig. 5 is an enlarged sectional view on 55 plane 5—5, Fig. 1 and

Fig. 6 is a section on line 6—6, Fig. 2.

My attachment requires no change or reconstruction of any kind in a buttonhole machine of the Reece type and I shall therefore more or less generally describe the construction and operation of the Reece machine to which I have shown my attachment applied, the machine itself being disclosed and its operation described in Reece Patent No. 655,637 of August 7th, 1900, and Hill 60 Patent No. 713,764 of November 18th, 1902. The stitch frame 10 overhangs at its front the work receiving table 11 and journals the needle bar 12 having at its lower end the needle 13, the bar being reciprocated by 65 mechanism described in the patent referred to and being rotated by the mechanism 14. The plates or feet 15 are provided for clamping the work on the table 11 and are operated all as fully disclosed in said patents. 70 16 is the cutter frame whose operating mechanism is not shown here. At the rear of the stitch frame is journaled the stitching shaft 17 adapted to be driven by a belt 18 on pulley 19, the clutch mechanism designated as a whole by 20 serving at the proper 75 time to connect the pulley with the shaft.

21 represents the feed shaft which extends transversely of the machine below the reciprocating table 22 which carries the 80 stitching frame 10. This feed shaft carries the worm 23 which meshes with the gear teeth (not shown) on the large cam 24 which controls the shifting of the table 22 and other operating mechanism, all as fully 85 disclosed in said prior patents referred to. At its outer end, the feed shaft has secured thereto, the arm 25 which has the clutch lug 26 secured thereto. Just within this arm the feed shaft carries the belt pulley 27 and 90 the hub 28, both loosely mounted on the shaft and the hub having the clutch tooth 29 extending through the opening 30 in the pulley for co-operation with the clutch tooth 26 on the arm 25 when the hub is 95 shifted outwardly on the shaft. When the clutch lugs are engaged the rotation of the pulley by the belt 31 will be communicated through the arm 25 to the feed shaft. At its inner end the hub receives the clutch collar 32 which is connected with the arm 33 of the clutching frame 34 which is pivoted at 35 as clearly indicated in Fig. 2. This clutching frame 34 and its functions are clearly disclosed in the prior patents referred 100 to. Like in said patents, its hook 36 receives the stud 37 adjustably secured on the clutch 105

releasing lever 38 and extending through the slot 39 in said lever. The clutch releasing lever is pivoted at 40 (Fig. 2) and at its front end is normally locked out by the 5 dog 41 extending from the starting lever 42, this normally positively holding stud 37 against the hook 36 to thereby normally lock the clutching frame 34 in unclutching position. The compression spring 43 tends to 10 swing the lever in clock-wise direction (Fig. 2) to hold the stud 37 against the hook 36 of the clutching frame.

At its other end the feed shaft is in connection with ratchet driving mechanism not 15 here shown but fully disclosed in said prior patents referred to, said ratchet mechanism being connected by means of the lever 44 and link 45 with the frame 46 in which rotates the cam 47 which is mounted on the 20 stitching shaft 17. This ratchet connection causes the stitching frame to be shifted intermittently forwardly and rearwardly during stitching of a buttonhole. At other times movement of the stitching frame is effected 25 when the feed shaft is rotated by the pulley 27.

Below the stitch shaft 17 is the rock shaft 48 from which extends the arm 49 carrying at its outer end the frame 50 forming part 30 of the clutch mechanism for connecting the pulley 19 in driving relation with the stitch shaft. The rock shaft also carries the three arm lever having the arms 51, 52 and 53, the arm 52 extending downwardly through 35 the slot 54 formed in the clutching frame 34. Below the rock shaft the bed of the machine supports the controlling bar 55 which has the incline 56, while at the left end of the arm 51 is located the mechanism 40 for co-operating with the controlling bar. This mechanism comprises the lever 57, the radius bar 58, and the spring 59 which connects the upper end of the bar with the tail 45 60 of the lever 57 and tends to hold the outer end of said lever down. At the lower end of the radius bar is the roller 61 for co-operating with the upper surface of the controlling bar 55. The lever 57 has the toe 62 and the notch 63 which notch normally receives the pin 64 on which the roller 50 61 is journaled. The lever 57 has also the other pin 65 which is normally held behind the post 66 extending from the machine bed.

On the arm 53 of the three-armed lever 55 is secured the stop block 67, while a spring 68 connects between the end of this arm and the stitching frame. On the bracket 69 supported on the stitching frame is pivoted the latch lever 70 which has the shoulder 71 for 60 receiving at a certain time the stop block 67. A spring 72 tends to swing the lever inwardly but normally a stop screw 73 abuts against the machine bed to hold the lever swung outwardly with its shoulder away 65 from the stop block as shown in Fig. 3.

The latch lever has the actuating arm 74 extending upwardly therefrom by means of which it may be manually rotated.

In the operation of the Reece machine to which I have applied my invention which shall be explained later, stitching for a buttonhole is first accomplished and then the hole is cut. Very often the stitching goes wrong, as for example, when the needle breaks or bends, or the thread tears, and it is then very important to immediately stop the stitching, and it is more important that operation of the cutting mechanism be blocked to prevent cutting of the buttonhole so as to permit removal of the false stitches before erroneous cutting of the cloth. In the machine to which my invention is applied, the operation of the stitching mechanism can be immediately stopped by swinging the actuating arm 74 of the latch lever 70 forwardly, but unless the operator stops the entire machine by actuation of the foot pedal, there is no assurance that operation of the cutting mechanism will be blocked in time to prevent cutting of the buttonhole. Erroneous cutting of buttonholes is, of course, a very serious matter as expensive work may be thus readily spoiled. It is the purpose of my invention to provide means not only for quickly stopping the stitching mechanism from a convenient position, but also for at the same time immediately blocking any such operation of the machine as would otherwise cause operation of the cutting mechanism.

Describing now my improved attachment, a shaft 75 extending longitudinally of the machine at one side of the base of the stitching frame, is journaled in the brackets 76 and 77, the bracket 76 being secured to the side of the stitching frame and the bracket 77 being clamped to the rear end thereof by means of a plate 78 and the clamping screws 79 which extend through the opening 80 in the rear wall of the stitching frame. At its front end the shaft 75 carries the actuating arm 81 by which it may be rocked, while at its inner end it has the upstanding arm 82 connected by link 83 with the bell crank shaped trip lever 84 which is pivoted at 85 on the end of the bracket 69. The inner end of the trip lever is behind the actuating arm 74 for the latch lever 70. The shaft 75 is intended to be rotated in clockwise direction looking from the front of the machine and on the link 83 is the abutment nut 86 for the cushion spring 87 which surrounds the link and engages against the rear end of the trip lever 84, the end of the link receiving the adjusting nut 88.

Secured to the shaft 75 are the collars 89 and 90 between which extends the cam bar 91. On the stationary bed plate of the machine is secured the bracket 92 in which is

journaled intermediate its ends the bar 93 whose inner end is in the path of the cam bar 91, a spring 94 tending to hold the bar in such cam bar engaging position. At its 5 outer end the bar has the laterally extending arm 95 having at its end the depending stop lug 96 which lug is in front of the rear end of the lever 38 when the bar 93 is engaged by the cam bar so that in such position of 10 these parts, the lug will prevent outward swing of the lever 38 at its rear end, the lever when thus locked having its stud 37 engaging with the hook 36 of the clutching frame 34 to hold said frame in its inner position 15 with the hub 28 in far enough to prevent co-operation of the clutch lug 29 with the lug 26 on the arm 25 extending from the feed shaft 21.

Normally the arm 81 is down with the 20 cam bar 91 in position to permit spring 94 to rotate the bar 93 to swing its detent end 96 away from the lever 38, as shown in dotted lines Fig. 6, the trip lever 84 being at the same time swung out of the path of the actuating arm 74, as shown in Fig. 4.

Briefly describing now the operation of the machine itself, and together with such operation the purpose and function and operation of my attachment, the operator first 25 inserts the piece of work under the clamping shoes 15 and then after actuating the foot pedal to connect a countershaft with the machine, she depresses the starting lever 42. This releases the lever 38 at its front end and 30 the pressure of the spring 43 against the lever is overcome by the pull of spring 97 on the clutching frame 34, this frame being then swung to cause outward shift of the hub 28 and projection of the clutch lug 29 into the 35 path of the lug 26 on the lever 25 so that the feed shaft 21 will be rotated. Swing of the clutch lever also brings the end of its slot 54 against the arm 52 of the stitching controlling mechanism. Immediately upon 40 rotation of the shaft 21 the cam 24 is rapidly rotated, and, as fully disclosed in the prior patents referred to, the stitching head frame together with its associated mechanism (Figs. 3 and 4) travels rearwardly and 45 eventually co-operates with the controlling bar 55 to rotate the rock shaft 48, and as soon as the rock shaft is rocked, the arm 49 is swung downwardly to move the clutch mechanism 50 to permit the belt 18 to rotate 50 the shaft 17 so that the stitching mechanism begins to operate. Also, as soon as the shaft 48 is rocked and before stitching begins, the depending arm 52 is swung and carried at 55 its lower end into engagement with the clutching frame 34 to swing said frame on its pivot 35 against the force of the spring 97, and upon swing of such frame the hub 28 is shifted inwardly to disconnect the pulley 27 from driving connection with the feed 60 shaft. 65

After starting of the machine the stitch frame travels rearwardly and the abutment screw 73 leaves the machine frame and permits the latch lever 70 to carry its shoulder 71 over the stop block 67 as shown in Fig. 70 4. The parts are then held in stitching operative position. After one side of the buttonhole has been stitched, the stitching head frame travels forwardly and the parts will again assume the normal position, the clutch 75 mechanism 50 being then released to stop the stitching operation and the rock shaft being turned back to cause the lever 52 to release the clutching frame 34 to permit the spring 97 to return the hub 28 so that the 80 high speed pulley 27 may again connect with the feed shaft, whereupon the knife mechanism is operated to cut the buttonhole and the machine is returned to normal position 85 ready for another buttonhole forming and cutting operation.

If, during the stitching operation the needle should bend or break or the thread should tear, or for any other reason, it becomes desirable to stop the stitching and to 90 prevent cutting so that any false stitching may be unraveled and the operation restarted correctly, the operator swings the arm 81 inwardly to rock the shaft 75. Such rocking causes inward shift of the link 83 and 95 rotation of the trip lever 84 with its inner end against the back of the actuating arm 74 of the latch lever 70, and this latch lever is swung rearwardly to the position shown in Figs. 1, 2 and 3 thereby effecting release 100 of the stop block 67 from the shoulder 71 and causing the stitching operation to be stopped and permitting sufficient rocking of the shaft 48 by spring 68 to enable the arm 52 to release the clutching frame 34 (Fig. 2). 105 If the clutching frame were allowed to swing outwardly the hub 28 would be shifted to bring the pulley 27 into driving connection with the shaft 21. However, such swing is prevented as when the shaft 75 is rotated 110 the cam bar 91 will be brought under the bar 93 and this bar will be swung to carry its stud 96 in front of the lever 38 (full lines Fig. 6), and the stud 37 carried by this lever being in front of the hook 36 of the clutching 115 frame, the frame is not permitted to swing and consequently clutching of the pulley 27 to the feed shaft is prevented.

Thus, by means of a simple attachment, the swing of a lever in a convenient position 120 for the operator will immediately stop the stitching operation and will also positively and immediately block operation of the cutting mechanism. The operator can then unravel the false stitching or properly reset 125 the work in the machine.

During the stitching operation, the clutching frame 34 travels with the stitching head but the lever 38 does not travel, and owing 130 to the relative position between the hook 36

and the stud 37 during stitching operation, the lever 38 cannot be swung sufficiently by its spring 43 to permit its outer end to return to locking engagement with the dog 41 of the starting lever 42. When the actuating arm of shaft 75 is released after stopping of the stitching operation, the machine can continue its operation and at the end of a cycle, the relative position of the stud 37 and hook 36 will permit sufficient swing of the lever 38 to enable its front end to be again latched and locked by the dog 41.

I claim as follows:

1. In a buttonhole sewing machine, the combination of stitching mechanism, setting mechanism for controlling the operation of said stitching mechanism, a latch lever for locking said setting mechanism in stitching operation position, cutting mechanism, driving mechanism therefor, clutch mechanism for controlling the connection of said cutting mechanism with its drive mechanism, and an attachment for the machine comprising a rock shaft having an actuating arm, a tripping lever associated with said latch lever, a train connecting said tripping lever with said rock shaft, rocking of said shaft causing operation of said tripping lever to release said latch lever to thereby stop operation of the stitching mechanism, a stop lug, and means controlled during rocking of said rock shaft to interpose said stop lug in the path of said clutching mechanism whereby to block operation of the cutting mechanism after stoppage of the stitching mechanism.

2. In a buttonhole sewing machine, the combination of stitching mechanism, setting mechanism for controlling the operation of said stitching mechanism, a latch lever for locking said setting mechanism in operative position, buttonhole cutting mechanism, driving mechanism for said cutting mechanism, clutch mechanism for controlling the connection of said cutting mechanism with said driving mechanism, a clutching frame connected with said clutching mechanism, means controlled upon setting of said setting mechanism for stitching operation to lock said clutching frame in unclutching position to thereby prevent operation of the cutting mechanism, a clutch lever having a stud cooperating with said clutching frame, a rock shaft on said machine, a tripping lever connected with said rock shaft and adapted to engage with and release the latch lever of the setting mechanism when said rock shaft is actuated, whereby the operation of the stitching mechanism is stopped, a stop lug, and means connecting said lug with said rock shaft for causing setting of said lug in the path of said clutch lever when the rock shaft is operated to thereby block return of said clutch frame to clutching position when said stitching mechanism is stopped, thereby preventing cutting of the buttonhole after partial or erroneous stitching.

In witness whereof, I hereunto subscribe my name this 3rd day of September, A. D. 1920.

CHARLES E. CASGRAIN.
